Addis.

UNITED STATES PATENT OFFICE.

ALEXANDER C. P. HAGUE, OF BOSTON, MASSACHUSETTS.

HOBBYHORSE.

Application filed September 19, 1927. Serial No. 220,326.

My invention relates to hobby-horses and similar devices having provision for progressing the same by power imparted by the rider.

5 The invention will be best understood from the following description when read in the light of the accompanying drawing of one embodiment of the invention, while the scope of the invention will be more particularly pointed out in the appended claims.

10 In the drawing:—

Fig. 1 is a side elevation of a hobby-horse constructed according to the invention;

15 Fig. 2 is a side elevation of the device according to Fig. 1, with parts broken away and parts in different positions;

20 Figs. 3 and 4 are sections on the lines 3—3 and 4—4 of Fig. 2, Fig. 4 being on an enlarged scale; and

Fig. 5 is a section on the line 5—5 of Fig. 4.

25 As illustrated the device comprises a body having a front member 1 and a rear member 3 connected by side members 5, the latter being cut away at their forward and rearward end portions to provide openings 7 and 8 through which respectively extend rocker-members 9 and 11. To the opposite ends of the members 9 and 11 respectively are rigidly secured the upper portions of rearward supporting legs 13 and forward supporting legs

30 15. As shown the members 9 have upper edges 17 in rolling contact with the upper edges 19 of the openings 7 and 8, the construction being such that when the legs are swung or oscillated alternately toward and away from each other in a vertical plane for progressing the device the body will not be substantially raised or lowered. The inclined side edges 21 of the members 9 and 11 coact with the corresponding side edges of the openings 7 and 8 so as to provide stops for limiting the swinging of the legs in opposite directions relative to the body.

35 40 As illustrated the device is provided with a support 23 for the body of the rider, said support herein termed a "saddle". Herein the forward portion of the saddle is pivoted at 25 to the body of the device, and at its under side is pivotally connected to the upper end of a link 27 the lower end of which carries a pin 29 slidably engaged with slots 31 formed in the ends of arms 33 which respectively are rigidly connected to the facing sides of the members 9 and 11 and extend toward the central part of the body to beneath

the saddle as clearly shown by Fig. 2 of the drawing.

45 As illustrated the device is provided with foot rests 35 for the rider, said foot rests herein termed "stirrups". As shown the stirrups are connected by straps 37 to the ends of arms 39 fixedly carried by a rock shaft 41 on the body, the rock shaft having a rearwardly projecting arm 43 in the path of a pin or roller 45 secured to the link 27. As 50 shown a stop 47 is provided for limiting upward movement of the arm 43.

55 As illustrated the legs 13 and 15 are provided with rollers 49 carried on pivot pins 51 secured to brackets 53 rigidly attached to 60 the ends of the legs, the opposite ends of the pins 51 extending beyond the brackets into slots 55 of side arms 57 of grip devices for the rollers having support engaging members 59 to which the arms are secured. The 65 construction is such that when the legs are swung rearward relative to the body the grip devices by reason of contact of the portions 59 thereof with the support for the device slide relative to the legs to bring said 70 portions into contact with the rollers and thus prevent rotation of the latter, while when the legs are swung forward the grip devices are moved out of contact with the rollers and permit rotation thereof.

75 80 In operation, assuming the parts are in the position shown by Fig. 2, if the rider permits his weight to be supported on the saddle the latter will descend and depress the arms 33, thereby swinging the legs apart into the 85 position shown by Fig. 1. During this movement the grip devices for the rollers 49 on the rear legs will prevent rotation of said rollers, and said rear legs will not move relative to the support for the device. The 90 rollers 49 on the front legs however are free to rotate during this movement of the legs, and therefore the front legs will move relative to the support for the device, which 95 will progress the device. When the saddle descends the pin 45 contacting with the upper 100 side of the arm 43 causes the stirrups to be raised into the position of parts shown by Fig. 1. With the parts in the position shown by Fig. 1 if the rider supports his weight on the stirrups 35 the latter will descend and by 105 reason of the connection of the same with the legs of the device and with the saddle will swing the legs toward each other and raise the saddle to position these parts as shown 110

by Fig. 2. During this latter movement of the legs the rollers 49 on the front legs are prevented from rotating, while the rollers on the rear legs are free to rotate, which will 5 prevent movement of the front legs relative to the support for the device while permitting movement of the rear legs relative to said support, thus causing further progression of the device.

10 It will be observed that the oscillatory movement of the legs for causing progression of the device is caused by the rider alternately supporting himself on the saddle and stirrups, which saddle and stirrups are operatively connected to the legs, and further that movement of the legs is accomplished without substantial raising or lowering of the body of the device, which raising and lowering if it occurred would necessitate raising and lowering of the rider. Thus with a device constructed according to the invention the effort of the rider is substantially wholly consumed in causing the progressive movement of the device without wasted effort in raising and 20 lowering the rider.

25 Although I have described but one embodiment of the invention it will be understood that wide deviations from this embodiment may be made without departing from the spirit of the invention.

Claims:

1. A device of the character described having, in combination, a body, front and rear legs for supporting said body, means for 25 swinging said legs relative to said body in vertical planes with the ends of said legs resting upon a support, and connections between said legs and body providing shifting horizontal pivots for said legs, which pivots 40 remain substantially fixed distances above the plane of said support in all angular positions of said legs relative to said body.
2. A device of the character described having, in combination, a body, front and 45 rear legs for supporting said body, means for swinging said legs relative to said body in vertical planes with the ends of said legs resting upon a support, and connections between said legs and body providing for pivoting 50 each leg about different horizontally spaced axes when said leg is in different portions of

its travel relative to said body whereby said device is progressed by swinging of said legs without substantial raising or lowering of said body.

3. A device of the character described having, in combination, a body, front and rear legs for supporting said body, means for swinging said legs relative to said body in vertical planes with the ends of said legs resting upon a support, and rocker connections between said legs and body providing for pivoting each leg about different horizontally spaced axes when said leg is in different portions of its travel relative to said body, whereby said device is progressed by swinging of said legs without substantial raising or lowering of said body.

4. A device of the character described having, in combination, a body, front and rear legs for supporting said body, means for swinging said legs relative to said body in vertical planes with the ends of said legs resting upon a support, means comprising cooperating parts carried by said legs and body 75 for pivotally connecting said legs to said body about horizontal axes when said legs are inclined forwardly relative to said body and about different horizontal axes spaced rearwardly from said first mentioned axes when 80 said legs are inclined rearwardly relative to said body, whereby said device is progressed by swinging of said legs without substantial raising or lowering of said body.

5. A device of the character described having, in combination, a body, front and rear legs for supporting said body, means for swinging said legs relative to said body in vertical planes with the ends of said legs resting upon a support, front and rear rocker 90 members respectively connecting said front and rear legs, said members having spaced portions cooperating with spaced portions on said body for providing forwardly and rearwardly shifting pivots as said legs are swung 95 correspondingly relative to said body, whereby said body is progressed by swinging of said legs without substantial raising and lowering of said body.

In testimony whereof, I have signed my 100 name to this specification.

ALEXANDER C. P. HAGUE.
